UNITED STATES PATENT OFFICE.

JACOB VICTOR MARYLAND, OF VIRGINIA, MINNESOTA.

SNOWPLOW.

1,396,377.

Specification of Letters Patent.

Patented Nov. 8, 1921.

Application filed March 18, 1920. Serial No. 366,785.

To all whom it may concern:

Be it known that I, JACOB VICTOR MARYLAND, a citizen of the United States, and a resident of Virginia, in the county of St. Louis and State of Minnesota, have invented certain new and useful Improvements in Snowplows, of which the following is a specification.

My invention is an improvement in snow plows, and has for its object to provide a device of the character specified adapted to be connected to the front of a motor vehicle and to be operated thereby, wherein mechanism is provided for steering the plow to permit it to follow turns in the road without strain on the plow and the motive power.

In the drawings:

Figure 1 is a top plan view of the improved plow;

Figs. 2, 3 and 4 are sections on the lines 2—2, 3—3 and 4—4, respectively, of Fig. 1;

Fig. 5 is a sectional view through one of the runners, showing the mounting of the same;

Figs. 6 and 7 are sections on the lines 6—6 and 7—7, respectively, of Fig. 5.

In the present embodiment of the invention the improved plow comprises a pair of similar wings or moldboards 1 which are rigidly connected at their forward ends, and, referring to Figs. 2, 3 and 4, it will be seen that these moldboards or wings are curved transversely and arranged with their concave faces outwardly. The curve is such, and they diverge from each other rearwardly at such an angle, that the snow will slide smoothly along the outer faces of the wings without bunching, and they are curved over sufficiently at the top, as shown more especially in Figs. 2 and 3, to prevent the snow from flying over the top on to the propelling power behind, in the event that the plow should be operated at a rapid speed.

Near their ends the wings are connected by angle plates 2 and 3, there being provided three plates of each series 2 and 3, two arranged near the top of the wings and one near the bottom. The angle plates at the top are oppositely arranged, as shown in Fig. 4, in spaced relation, and each pair of angle plates 2 carries a nut 5, which is journaled in bearing arms 6 secured to the angle plates of the pair. These nuts, as shown in Fig. 5, have their ends reduced,

to engage openings in the bearing plates and each nut has rigid therewith a wheel 7 for turning the same.

A shaft 8 is supported by the nut 5 at the front of the wings and by a bearing arm 6^a on the lower angle bar 2, this shaft 8 having threaded engagement with the nut.

Similar shafts 9 are supported by the nuts 5 at the rear of the wings, and by the lower angle bar 3, and each of these shafts 9 has at its upper end a radial arm 10. The shaft 8 has at its upper end a pair of arms 11 extending at approximately a right angle with respect to each other, each of the arms 11 being connected by a link 12 with the arm 10 of the adjacent shaft 9.

A shoe or runner 13 is carried by each shaft 8 and 9. These runners are similar, each consisting of a sheet of metal of suitable weight having its ends upturned as shown and curved transversely and arranged with its concavity downward, and each shoe carries intermediate its ends a bearing lug 14. Each of these lugs 14 is received between a pair of lugs 15 on the lower end of the adjacent shaft or post 8 or 9, as the case may be, the lugs being pivotally connected, as shown, to permit the shoe or rocker to swing on an axis transverse to the direction of motion of the plow.

The link connection 12 between the shafts 8 and 9 constrains them to move together, and the concave surface of the runner prevents lateral slip of the plow when turning. Mechanism is provided for connecting the plow to the front of a motor vehicle, indicated at 16. The connection is through the angle bar 4. This bar has near each end hinge lugs 17 which receive between them the forward ends of the side members 18 of a connecting frame consisting of said side members and inclined braces 19.

The said forward ends of the side members are pivoted to the hinge lugs and at their rear ends the side members are pivoted between the arms 20 of yokes, whose bodies 21 are clipped to the front ends of the springs, by means of clips indicated at 22. Both of these hinge connections at the hinge leaves 17 and at the yoke 21 are horizontal and transverse to the direction of motion of the plow, so that the plow may move freely vertically with respect to the vehicle.

Mechanism is provided for permitting the plow to be steered from the driver's seat of the vehicle. The said mechanism consists

of a radial arm 23 on one of the shafts 9, which has at its outer end a series of openings, as shown in Fig. 1. A link, consisting of sections 24 and 25, connects this arm with the connecting rod 26 which connects the steering wheel with the steering knuckle of the vehicle. The sections 24 and 25 of the link are connected by a ball and socket joint 27, to permit free movement of the plow 10 with respect to the vehicle.

The series of openings in the arms 23 permits the section 24 of the link to be adjusted, to vary the relative movement of the steering shaft and the arm 23. The point 15 of the plow is curved upwardly, as shown at 28, to prevent the point from sticking into obstacles on the road, and a brace 29 connects this up-curved point to the front of the plow. This upturned point 28 is provided 20 with an opening 30 for engagement by draft apparatus to pull the plow when necessary. The improved plow can be either pushed or pulled, but it is primarily constructed for use with motor trucks or tractors.

25 In operation, when pushed, the parts are arranged as shown in Fig. 1. From the driver's seat he may steer the plow as well as the vehicle. The snow glides up the concave faces of the wings and moves rearwardly, being deposited at each side of the track formed by the plow. If it is desired 30 to pull the plow, draft apparatus is connected with the opening 30 of the turned up point of the plow.

35 I claim:

1. A snow plow comprising a pair of wings or shares meeting at an acute angle, and curved to smoothly deflect the snow to either side, a rigid connection between the 40 said wings, means for connecting said plow to a motor vehicle to permit the plow to move freely vertically with respect to the vehicle, steering devices for the plow, and

means for controlling said devices from the motor vehicle, said steering devices comprising shoes curved transversely and arranged with their concave faces downward, a shoe being arranged at each corner of the plow, and being connected to swing simultaneously in the same direction. 50

2. A snow plow including a pair of wings, a rigid connection between said wings at the forward end of the plow, a rigid connection between said wings at the rear end of said plow, a vertical shaft rotatably mounted on the connections at the forward end, a pair of vertical shafts rotatably mounted on the rigid connection at the rear, guiding shoes carried at the lower end of the vertical shafts, crank arms carried by said 60 shafts, links connecting said crank arms, and common controlling means for said shafts.

3. A snow plow comprising a pair of wings, a rigid connection between said wings including spaced angle plates, bearing arms carried by said angle plates, nuts journaled in said bearing arms, vertical shafts, each having a threaded portion operatively engaged with a nut, a guide shoe, means for pivotally mounting the guide shoe 70 on the lower end of said shaft including a lug carried by the shaft, and a pair of lugs carried by the guide shoe and embracing and pivotally secured to the lug of the shaft, and means for controlling said shaft 75 including an arm carried by the upper end thereof.

4. A snow plow comprising a pair of wings, rigid connections between said wings, vertical shafts rotatably journaled on said 80 rigid connections, means for constraining said shafts to corresponding motion, guide shoes, and means for pivotally connecting said guide shoes to said shafts.

JACOB VICTOR MARYLAND.
